(57) **CLAIM**

The ornamental design for a tunnel for a playset, as shown and described.

DESCRIPTION

FIG. 1 is a front perspective view of a tunnel for a playset; FIG. 2 is a front view of FIG. 1; FIG. 3 is a back view of FIG. 1; FIG. 4 is a right side view of FIG. 1; FIG. 5 is a left side view of FIG. 1; FIG. 6 is a top view of FIG. 1; and, FIG. 7 is a bottom view of FIG. 1. The broken lines in the Figures illustrate portions of a playset that form no part of the claimed design.
